UNITED STATES PATENT OFFICE

97,305

DESIGN FOR A DRESSING TABLE BOX OR SIMILAR ARTICLE

Jacob Rubin, Brooklyn, N. Y.

Application August 7, 1935, Serial No. 57,989

Term of patent 7 years

To all whom it may concern:

Be it known that Jacob Rubin, a citizen of the United States and resident of Brooklyn, in the county of Kings and State of New York, has invented a new, original, and ornamental Design for a Dressing Table Box or Similar Article, of which the following is a specification, reference being had to the accompanying drawing, forming part thereof, in which,

The figure is a perspective view of a dressing table box embodying my new design.

The dominant feature of the design is the effect produced by the use of a substantially circular mirror upstanding centrally from the rear end of the box in combination with the flat mirror on top thereof.

I claim:

The ornamental design for a dressing table box or similar article substantially as shown and described.

Dated, New York city, August 6th, 1935.

JACOB RUBIN.
